UNITED STATES PATENT OFFICE

101,251

DESIGN FOR A BURIAL VAULT

Harry Cohen, Galion, Ohio, assignor to The Perfection Steel Body Company, Galion, Ohio, a corporation

Application February 26, 1936, Serial No. 61,367

Term of patent 14 years

To all whom it may concern:

Be it known that I, Harry Cohen, a citizen of the United States, residing at Galion, in the county of Crawford and State of Ohio, have invented a new, original, and ornamental Design for Burial Vault, of which the following is a specification, reference being had to the accompanying drawing, forming a part thereof, in which—

The figure is a perspective view of a burial vault showing my new design.

The end portion of the burial vault opposite that shown in the drawing herein is the same as the end portion shown. The side portion opposite that shown in the drawing is likewise the same as that shown.

The characteristic feature of my burial vault invention is indicated in solid black lines.

I claim:—

The ornamental design for a burial vault, substantially as shown, and described.

HARRY COHEN.
